UNITED STATES PATENT OFFICE.

JAMES FAZIO, OF LOS ANGELES, CALIFORNIA.

DESIGN FOR A DISPENSING STAND.

Application filed August 12, 1922. Serial No. 3,365. Term of patent 7 years.

To all whom it may concern:

Be it known that I, JAMES FAZIO, a citizen of the United States, residing at Venice, in the county of Los Angeles and State of California, have invented a new, original, and ornamental Design for a Dispensing Stand, of which the following is a specification.

The drawing illustrates a stand in the form of a casing to enclose mechanism to be used to attract attention to the sale of fruit juice.

Fig. 1 is a front elevation of a dispensing stand showing my new design.

Fig. 2 is a side elevation of the stand in Fig. 1.

I claim:

The ornamental design for a dispensing stand as shown.

JAMES FAZIO.
